(57) **CLAIM**

What is claimed is the ornamental design for a base plate element for decorations or ornaments, as shown and described.

DESCRIPTION

FIG. 1 is a perspective view of a base plate element for decorations or ornaments showing my new design;

FIG. 2 is a top plan view thereof;

FIG. 3 is a front elevational view thereof, the rear elevational view thereof being a mirror image;

FIG. 4 is a right side elevational view thereof, the left elevational view thereof being a mirror image; and,

FIG. 5 is a cross sectional view taken along line 5—5 of FIG. 1.
